UNITED STATES PATENT OFFICE.

AUDREY KINGSBURY, OF NEW YORK, N. Y.

DESIGN FOR A COMBINED HOOD AND WAIST.

41,930.

Specification for Design.

Patented Nov. 14, 1911.

Application filed June 27, 1911. Serial No. 635,669. Term of patent 7 years.

To all whom it may concern:

Be it known that I, AUDREY KINGSBURY, a citizen of the United States, residing in New York city, in the county of New York and State of New York, have invented a new, original, and ornamental Design for a Combined Hood and Waist, of which the following is a specification, reference being had to the accompanying drawing, forming part thereof.

The figure is a perspective view of a lady's waist showing my new design.

I claim:

An ornamental design for a combined hood and waist, as shown.

AUDREY KINGSBURY.

Witnesses:

F. C. CADDENS,
Wm. H. JEFFERS.
